UNITED STATES PATENT OFFICE.

EDMUND HOFFMAN, OF BROOKLYN, NEW YORK, ASSIGNOR TO AMERICAN CAN COMPANY, OF NEW YORK, N. Y., A CORPORATION OF NEW JERSEY.

DESIGN FOR A BOX.

46,866.

Specification for Design.

Patented Jan. 19, 1915.

Application filed September 16, 1914. Serial No. 862,116. Term of patent 7 years.

To all whom it may concern:

Be it known that I, EDMUND HOFFMAN, a citizen of the United States, residing at Brooklyn, in the county of Kings and State of New York, have invented a new, original, and ornamental Design for a Box, of which the following is a specification, reference being had to the accompanying drawing, forming a part thereof.

On the drawing, Figure 1 is a side eleva-

tion of a box constructed in accordance with my invention and Fig. 2 is a top plan view of same.

I claim:—

The ornamental design for a box, as shown.

EDMUND HOFFMAN.
